EXTENSION TABLE

Irving Segal, New York, N. Y.

Application June 2, 1933, Serial No. 673,958

5 Claims. (Cl. 311—58)

This invention relates to extension tables and more particularly to an improved automatically operated leaf which is adapted to extend from one side of the table top.

5 One object of the invention is to support a leaf beneath one side of a table on angularly disposed members which are oppositely movable with the table top and are adapted to project or extend said leaf beyond the edge of one side thereof.

10 Another object is to provide means whereby said leaf is raised to the plane of the table top when projected and means to lower said leaf when retracting same.

15 With the above and other objects not specifically referred to in view, the invention consists in certain novel parts, arrangements and combinations which will be fully described in connection with the accompanying drawing and the novel features pointed out in the claims hereunto annexed.

20 In the drawing which shows a preferred embodiment of the invention;

Fig. 1 is a plan view of a table with parts broken away and showing a leaf concealed beneath one side.

25 Fig. 2 is a side elevation of Fig. 1, with parts of the legs broken away.

Fig. 3, 4, 5 and 6 are sectional views taken on the line A—A of Fig. 1, and show the various 30 movements of the leaf as it is being projected and retracted.

Fig. 7 is a cross section taken on the line 7—7 of Fig. 1.

The table generally comprises a movable top 35 11, legs 12, and aprons 13 joining said legs. Said movable top is mounted on a pair of outside slide members 14, which are slidably mounted on stationary bars 15, supported by the aprons 13. Another pair of slide members, which will be referred to as inside slide members 16 are also slidably mounted on the support bars 15 and are the means for moving the auxiliary leaf, to be hereinafter described. By means of toothed racks 17 secured to the slides 14 and 16, and a pinion 18 40 45 rotatably mounted on stationary supports 15, any movement of the table top 11, attached to the outside slides, will cause a similar and opposite movement to the inside slides.

An auxiliary leaf 19, is pivotally mounted at one 50 end 22 of a pair of arms 21, and the opposite end of the arms 21 are pivotally secured to the inside slides 16 at 23. A projecting strap 24 secured to the lower surface of the auxiliary leaf 19, has a pendant 25 hanging from the lower surface thereof. Said pendant comprises a substantially in-

verted V shaped structure having one cam finger 26 and a hook 27, and is pivotally mounted upon a stud 28. A stop lug 29 is secured to the lower surface of the support 15, and projects into the path of the pendant 25, and when the leaf is moved to a projected or a retracted position the pendant will engage said stop in either direction and by its engagement will either raise or lower said leaf.

5 It will be observed that the arms 21 are positioned in an angular relation and the outer ends are moved angularly outward and upward to bring the outer end of the leaf up to the desired height, level with the table top before the pivotal movement of said leaf about the pivot 22 takes place, to move the leaf into the same plane as the table top.

10 Referring now to the various positions shown in Figs. 2 to 6, the position of Fig. 2 shows an elevation of the parts in a normal or closed position, 15 with the leaf 19 resting on the upper edge of the aprons 13 and confined within a cavity 31, formed within the table top.

15 When operating the table to extend the leaf, either the leaf or the table top may be grasped 20 to perform the necessary projecting and retracting operations. If the table top is grasped at the end indicated at B, and pulled outward, the movement will cause the slides 14 and 16 to be moved in opposite directions and thus move the leaf 19 25 outward in an angular direction as shown in Fig. 3. A continued outward movement of the table top will cause the cam finger 26, of the pendant 25, to engage the stop lug 29 and raise the projecting strap 24 on the leaf, thereby causing the 30 leaf 19 to rock about its pivots 22.

35 A U shaped member 32, has its free ends 30 in pivotal engagement with the arms 21 and has springs 33 secured to the bar 34 forming the closed end of same. The opposite end of said springs 40 are anchored on pins 20 projecting from the pivotal portions 23. Said U shaped arm is maintained in engagement with the projecting strap 24 by some suitable means such as a clip 37, so that it may be moved therewith.

45 The upward movement of the leaf, due to the engagement of the cam finger 26 with the stop lug 29 as previously described, will also cause the springs 33 or the U shaped members 32 to be moved above their dead center and consequently 50 cause same to be tensioned to exert an upward pressure on the projecting strap 24, to hold same in engagement with the under surface of the table top as shown in Fig. 4, and thereby hold said leaf in the same plane as the table top. A 55

slight inward movement of the table top will then bring the edges 35 and 36 of the leaf and table top into overlapping engagement as shown in Fig. 5.

- 5 It will be noted in Fig. 5 that the hook portion 27 of the pendant 25 is in approximate engagement with the stop lug 29 and that when it is desired to move the leaf 18 to its normal position beneath the table top, an initial pull outward 10 of the table top will cause the hook 27 to engage the stop 29 and pull the projecting arms and leaf 19 downward. This will cause the springs 33 to be moved slightly below their dead center to maintain the parts in the position shown when 15 the leaf is moved inward. After moving said leaf inward it will again assume the position shown in Fig. 2.

It will thus be observed that the operator can 20 manipulate the movement of the leaf 19 from one end of the table and all operations required to project and retract the leaf, with the exception of the manual movement of the table top, are automatic.

It will also be observed that there will be a 25 natural tendency for the leaf to remain in close fitting engagement with the table top when open as indicated in Fig. 5, due to the inclined position of the supporting arms 21.

While the invention has been shown and 30 described in its preferred form, it will be understood that certain changes and variations may be made in the specific structure provided for carrying out the invention, without however departing from the spirit of the invention as defined in the 35 appended claims.

Having thus described this invention, what is claimed is:

1. In an extension table, a movable table top, 40 an auxiliary leaf normally concealed beneath said table top and oppositely movable therewith when projecting same, means actuated by the movement of said table top for elevating said leaf to the plane of the table top when projected and

means actuated by the movement of the table top for lowering said leaf to retract same.

2. In an extension table, a movable table top, 5 an auxiliary leaf normally concealed beneath one side of said table top and oppositely movable therewith when projecting same, means actuated by the movement of said table top for elevating said leaf to the plane of the table top when projected and means actuated by the movement of the table top for lowering said leaf to retract same. 10

3. In an extension table, a movable table top, 15 an auxiliary leaf normally positioned beneath one side of said movable top and oppositely movable therewith when projecting and retracting same, means on said auxiliary leaf adapted to raise said leaf to the plane of the table top when projected and to lower said leaf when retracting same.

4. In an extension table a movable top, an auxiliary leaf normally positioned beneath one 20 side of said movable top and oppositely movable therewith when projecting and retracting same, a stationary stop member, means on said auxiliary leaf adapted to engage said stop and to be raised thereby to an elevated position when projected and also adapted to lower the leaf by engagement with said stop when retracting same. 25

5. In an extension table, a movable table top, 30 an auxiliary leaf normally positioned beneath one side of said table top, an angularly disposed support for said auxiliary leaf oppositely movable with said movable table top and adapted to extend said leaf beyond the side edge of the table top, a cam member movable with said auxiliary leaf and a stop adapted to be engaged by said cam member to move said leaf to the plane of the table top when extended, a spring actuated member to maintain said leaf in a raised position and a hook portion on said cam member adapted to engage said stop to lower said leaf when retracting same. 35 40
